UNITED STATES PATENT OFFICE

2,444,961

TOY RAILROAD ACCESSORIES

Richard G. Smith, Amsterdam, N. Y.

Application September 21, 1944, Serial No. 555,068

15 Claims. (Cl. 46—216)

1

The present invention relates to toy railroad accessories, and is more particularly directed toward toy railroad accessories including a toy railroad car which can be automatically unloaded preferably onto a platform alongside the track. It is customary to handle milk and cream in cans carried in express or freight cars, and in such railroad operations as the cans cannot be tipped over or rolled on their sides, they are unloaded by rolling them on their chimes from inside the car onto an unloading platform alongside the track.

The present invention is more particularly directed toward a combined toy car and toy unloading platform designed to carry out operations simulating the customary operation of unloading milk cans from milk cars.

In carrying out the above objects the present invention contemplates the inclusion in the track layout of a toy platform carried alongside the track layout in a fixed position relative to the rails and having an elevation above the track level the same as that of the car platform. The car which may form a part of a train outfit is provided with a magazine into which a number of articles simulating milk cans may be inserted. As the unloading of milk cans from railroad cars is accomplished in such a manner that the cans themselves always rest on their bottoms while being unloaded, the present invention contemplates an arrangement whereby each can is moved laterally from inside the car over onto the unloading platform without being tipped or tilted. As the unloading platform should be spaced some distance from the sides of the car body there is a space between the car platform and the unloading platform.

According to the present invention the mechanism utilized in unloading the toy "cans" is normally housed inside the car and is first moved to a position in which the space between the car body and unloading platform is bridged, and the toy milk can is at the same time shifted from inside the car outside the car while the can is supported from underneath. Then a can pusher, which can be made up to simulate an attendant on the car, engages the toy can and pushes it quickly over onto the unloading platform where it slides across the platform.

The present invention contemplates that the cans will be unloaded one at a time so long as there are cans in the magazine and one desires to operate the unloading apparatus. This apparatus preferably includes an electromagnet or solenoid for effecting the unloading operation

2

and a restoring spring for bringing the parts back to normal position.

The accompanying drawings show, for purposes of illustrating the present invention, an embodiment in which the invention may take form, it being understood that the drawings are illustrative of the invention rather than limiting the same.

In these drawings:

10 Figure 1 is a perspective view showing an unloading platform and car;

Figure 2 is a top plan view of the platform and car, the body of the car having been removed to show interior construction, the parts being shown in the normal position in full lines and in dotted lines in the position where the support for the toy article bridges the space between the car platform and unloading platform;

Figure 3 is a fragmentary view showing the parts in full lines in the position shown in dotted lines in Figure 2;

Figure 4 is a fragmentary view showing the parts in the fully extended position for unloading the toy milk can;

25 Figures 5, 6 and 7 are transverse sectional views on the lines 5—5, 6—6 and 7—7, respectively, of Figure 2;

Figure 8 is a longitudinal sectional view on a broken line 8—8 of Figure 2; and

30 Figure 9 illustrates a modified track arrangement and wiring diagram.

The usual wheel bearing rails for toy railroad track layout are indicated at 10, 10 and the third rail at 11. The track section carrying the rails indicated also supports an unloading platform designated generally by the reference character 12. It is secured to the track in any convenient manner.

40 A car 13 having the usual trucks 14 is carried on the track. The car platform 15 is at the same elevation as the top 16 of the unloading platform. The car body 17 has a loading opening 18 and a discharge or unloading opening 19 in its side-wall as indicated in Figure 1.

45 Car carried apparatus for handling the toy milk cans is here shown as being supported from a frame 20. This frame has a side wall 21 adapted to extend lengthwise of the car along the side of the car having the openings 18 and 19. It has a filling opening 22, Figure 8, opposite the filling opening 18 in the car body, and its right-hand end 23 is adjacent the discharge opening 19 of the car body.

50 A plate 24 is fastened to the side plate 21 and is shaped to form a longitudinally extending maga-

zine 25 of rectangular cross section, as more clearly illustrated in Figure 7. It is adapted to receive a number of toy cans as indicated by the letter C. These cans are urged to the right, as shown in the drawings, by a spring 28 acting on a follower 27, adapted to be latched in the left position shown in Figure 8 by a catch indicated at 28.

Opposite the side wall 21 of the frame 20 is another shorter side wall 30 which supports a solenoid coil 31 having a plunger 32 surrounded by a spring 33 and acting on a short arm 34 pivoted at 35. The short arm 34 is rigidly connected to a long arm 36 which extends beyond the end of the magazine and is adapted to be swung back and forth by the solenoid and spring.

Pivoted about the same axis 35 is a plate 37 which extends over the same distance as the arm 36. The plate 37 carries an angle-piece 38 pivoted at 39. When the parts are in the position shown in Figures 2, 5 and 6, the vertical part 38a of the angle-piece 38 is in front of the end of the arm 36, and the horizontal portion 38b rests on the car platform 15 so that the members 36 and 37 are interlocked and must swing as a unit. The car platform has a hole 40 through which the arm 38b of the angle-piece 38 drops when the parts are moved to the position indicated in Figure 3, thereby releasing the arm 36 so that it can move forwardly independent of the plate 37.

During the initial movement of the interlocked parts 36 and 37 the latter carries with it an article support 41 shown integrally therewith. It extends across the car platform 15 and out underneath the side wall of the car where it may be bent down, as indicated at 41', to provide a stop. It is in a position to receive the article C pushed out of the magazine by the follower 27. The toy can is received from the magazine by a figure 42 made up to simulate a man grasping a milk can. This figure is carried on a forwardly extending bracket 43 which is secured to the end of the arm 36. This bracket 43 has an opening 44 to accommodate the angle-piece 38.

The plate 37 carries a member 45 which is adapted to engage the side of the magazine to provide a stop for the plate 37 and its end extends over the end of the magazine, as indicated in Figures 3 and 4, to close off the end of the magazine.

In order to operate the device when the car is in the proper position along the track the track is provided with a supplemental contact rail 50 and the car with an insulated contact 51 connected to the coil 31 and adapted to engage this supplemental rail. The supplemental rail 50 is connected through a suitable switch so that the solenoid 31 can be energized as desired. If desired, the arrangement of Figure 9 may be employed.

In the operation of the device a suitable number of articles simulating milk cans are placed in the magazine and the follower 27 released so as to urge the cans out of the magazine. One can will therefore be on the article support 41 and held stationary by the can pusher 42. When the coil 31 is energized all the parts movable about the pivot 35 operate in unison until the interlock between the parts 36 and 37 opens as above described. At this time the article support has been moved across the space between the car platform and the unloading platform, the can is now out of the car body and the magazine is closed, as indicated in Figure 3. The continued movement of the arm 36 and can pusher 42 from

the position of Figure 3 to the position of Figure 4 pushes the can off its support and on to the unloading platform, and as this is accomplished at high speed the toy can slides across the platform so as to be out of the way of the next can being unloaded. The return of the parts to normal position is accomplished by the spring 33. The arm 36 first moves back and brings the rear edge of the pusher 43 against a flange 52 carried by the plate 37 and this plate is then carried back to the normal position and the interlock restored to its normal position.

In the arrangement shown in Figure 9, the unloading platform 16a is carried alongside a five-rail track section 53. The wheel bearing rails are shown at 54 and 55, the power rail at 56, one full length supplemental rail at 57 and a short supplemental rail at 58. These rails are connected to a controller C' in the same manner as shown in the Bonanno Patent 2,232,508, of February 18, 1941. The car trucks 60 and 61 are connected to the coupler coils at 62 and 63 and contact rollers 64 and 65. These rollers are connected to unloading coil 66 which functions the same as coil 31. The length and position of short rail 58 is such that unloading coil 66 can be energized by the controller C' only when the car is in the proper position relative to the unloading platform 16a.

Since it is obvious that the invention may be embodied in other forms and constructions within the scope of the claims, I wish it to be understood that the particular form shown is but one of these forms, and various modifications and changes being possible, I do not otherwise limit myself in any way with respect thereto.

What is claimed is:

1. In combination, a toy railroad track, a toy car having the usual trucks on the track and a car platform supported above the track, a toy unloading platform at the height of the car platform and having a fixed position relative to the track whereby a space of substantial width is provided between the car platform and the unloading platform, the car having an article support laterally movable from a position above the platform of the car across said space whereby an article on the support can be moved toward the unloading platform, a pusher for pushing the article off the article support and onto the unloading platform, and common operating means for both the article support and pusher.

2. The combination of claim 1, wherein the car has a magazine for several articles, and means for urging the articles from the magazine to the article support.

3. The combination of claim 1, wherein the car has a magazine for several articles, means for urging the articles from the magazine to the article support, and means movable with the article support for closing the discharge end of the magazine when the article support is moved out of its retracted position.

4. In combination, a toy railroad track, a toy car having the usual trucks on the track and a car platform supported above the track, a toy unloading platform at the height of the car platform and having a fixed position relative to the track whereby a space of substantial width is provided between the car platform and the unloading platform, the car having an article support laterally movable from a position above the platform of the car across said space whereby an article on the support can be moved toward the

unloading platform, a pusher for pushing the article off the article support and onto the unloading platform, an electromagnet for shifting the article support and pusher toward the unloading platform, and a spring for retracting them.

5. The combination of claim 4, wherein the track and car have cooperative contacts in the circuit for the electromagnet engageable only when the article support is opposite the unloading platform.

6. In combination, a toy railroad track, a toy car having the usual trucks on the track and a car platform supported above the track, a toy unloading platform at the height of the car platform and having a fixed position relative to the track whereby a space of substantial width is provided between the car platform and the unloading platform, the car having an arm pivoted to swing about a vertical axis and extending lengthwise of the car immediately above the car platform, an article support at the end of the arm and laterally movable from above the car platform across the space whereby an article on the support may be moved toward the unloading platform, a stop limiting the movement of the arm, a pusher pivoted about the same axis, means releasably interlocking the pusher and arm to make them swing in unison until the stop is reached and then releasing whereby the pusher can continue its movement and push the article onto the unloading platform, and means for operating the pusher.

7. The combination of claim 6, wherein the pusher operating means includes an electromagnet and a restoring spring.

8. In a toy for simulating the unloading of milk cans from a milk car, a toy milk car, a toy track, a toy milk can platform alongside the track, a car carried figure behind an opening in the side wall of the car representing a man unloading milk cans and having a base adapted to support a toy milk can, means to suddenly shift the figure and toy milk can from within the car to a position above the platform with the can supporting base close to the platform and to abruptly stop the figure so that the toy milk can slides off the base and onto the platform.

9. A toy car having a car body with a side opening, an article support normally inside the car in a position to support an article just inside the opening and laterally shiftable to transport the article beyond the outside of the car body, a pusher behind the article and interlocked with the movable article support to shift with it during its outward movement, a stop limiting the movement of the article support, means for releasing the interlock at the limiting position of the article support, and pusher actuating means for continuing the movement of the pusher to push the article off the article support.

10. A toy car as claimed in claim 9, having a magazine for delivering articles to the article support, and a closure device movable with the article support for closing off the magazine when the article support is out of normal position.

11. An unloading toy vehicle having laterally shiftable means to support an article within the side walls of the vehicle and adjacent an opening thereon, means to shift the supporting means and article through said opening, and means to impart

a sudden movement to the article in a direction to eject it laterally from the article support.

12. An unloading toy vehicle having laterally shiftable means to support an article within the side walls of the vehicle and adjacent an opening thereon, electromagnetic means to shift the supporting means and article through said opening and to thereafter impart a sudden movement to the article in a direction to eject it laterally from the article support, and a spring for retracting the ejecting and shifting means.

13. A toy electric railway car having a platform, a car body above the platform provided with an inlet opening and an outlet opening in one of the side walls, a magazine extending from the inlet opening to the outlet opening, a follower for pushing articles in the magazine toward the outlet opening, a laterally movable article support positioned to receive the articles from the magazine, an article pusher against which the article is brought when discharged from the magazine, means to shift the article support and pusher laterally to shift the article outside the car, a magazine closer for stopping egress of articles from the magazine when the article support is so shifted, means to stop the article support, and means to continue movement of the pusher.

14. A toy electric railway car having a platform, a body above the platform provided with an inlet opening and an outlet opening in one of the side walls, a magazine extending from the inlet opening to the outlet opening, a follower for pushing articles in the magazine toward the outlet opening, a laterally movable article support positioned to receive the articles from the magazine, an article pusher against which the article is brought when discharged from the magazine, an electromagnet for shifting the pusher from within the car to an extended position outside the car, spring return means for the pusher, and an interlock between the pusher and support requiring them to move in unison between their inner positions and a less extended position.

15. Mechanism for discharging a toy milk can or the like from a car body enclosed supporting plate on which it is adapted to rest including an arm connected to the plate and pivoted at its remote end so that the plate moves in a direction transverse of the car body, a pusher immediately above the plate and engageable with the rear of the article, the pusher being mounted on another arm pivoted concentrically with the first arm, a solenoid acting on the second arm to swing it back and forth and shift the pusher through an extended arc, an interlock between the pusher and article support to cause them to move in unison for part of their movement and releasing the pusher so it may overtake the support and push the article off it, and a restoring spring acting on the second arm.
